Fig. 4

Fig. 3

Fig. 5

FIG. 6

FIG. 7

FIG. 8

FIG. 9

FIG. 10

FIG. 11

FIG. 12

FIG. 1 is a frontal perspective view of a beverage dispenser showing my new design;

FIG. 2 is a top plan view thereof;

FIG. 3 is a frontal elevation view thereof;

FIG. 4 is an elevational view thereof taken from the end as seen from the right of FIG. 3, the opposite end being a mirror image thereof;

FIG. 5 is a cross sectional view thereof taken along line 5-5 in FIG. 3;

FIG. 6 is a frontal perspective view of a modification of the beverage dispenser of FIG. 1 wherein same is of lesser height and width;

FIG. 7 is a frontal elevation view thereof;

FIG. 8 is an elevational view taken from the end as seen from the right of FIG. 7, the opposite end being a mirror image thereof;

FIG. 9 is a cross sectional view taken along line 9-9 in FIG. 8;

FIG. 10 is a frontal perspective view of a further modification of the beverage dispenser of FIG. 1 wherein same is of lesser width;

FIG. 11 is a front elevational view thereof;

FIG. 12 is a cross sectional view taken along line 12-12 in FIG. 11;

The rear of the beverage dispenser in each of its embodiments is substantially flat and plain in appearance.

I claim:

The ornamental design for a beverage dispenser, substantially as shown and described.
